Primary Examiner — Mary Ann Calabrese*Assistant Examiner* — Katelin G Kloberg(74) *Attorney, Agent, or Firm* — JCIPRNET(57) **CLAIM**

The ornamental design for an bedside crib as shown and described.

DESCRIPTION

FIG. 1 is a perspective view of a bedside crib, showing our new design in a first condition of use;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view the bedside crib, showing our new design in a second configuration of use;

FIG. 9 is a front view thereof; and,

FIG. 10 is a right side view thereof.

The broken lines in FIG. 6 depict a portion of the bedside crib that form no part of the claimed design.

1 Claim, 10 Drawing Sheets(56)
